UNITED STATES PATENT OFFICE.

CLARENCE E. BEMENT, OF LANSING, MICHIGAN.

SEAT FOR HARROW-TEETH.

SPECIFICATION forming part of Letters Patent No. 410,141, dated September 3, 1889.

Application filed March 5, 1889. Serial No. 301,864. (No model.)

To all whom it may concern.

Be it known that I, CLARENCE E. BEMENT, a citizen of the United States, residing at Lansing, in the county of Ingham and State 5 of Michigan, have invented certain new and useful Improvements in Seats for Harrow-Teeth; and I do hereby declare the following to be a full, clear, and exact description of the invention, such as will enable others skilled in 10 the art to which it appertains to make and use the same.

This invention has relation to seats for harrow-teeth, and more particularly to that class thereof commonly known as "pivoted."

15 Among the main objects in view are to cheapen and simplify the seat, adapt the same for the reception and rigid retention of a tooth, and so construct said seat as to be capable of being set or disposed at different angles, where- 20 by the tooth is presented at different inclinations.

Other objects and advantages of the invention will hereinafter appear, and the novel features will be particularly pointed out in 25 the claims.

Referring to the drawings, Figure 1 is a side elevation of a harrow-tooth seat, the same being applied to a bar and holding a tooth, the seat being constructed in accordance with 30 my invention. Fig. 2 is a plan of the same, and Fig. 3 is a perspective in detail of the seat.

Similar letters of reference indicate similar parts in all the figures of the drawings.

35 A represents any ordinary harrow beam or bar, which at intervals is provided with openings A', (see dotted lines, Fig. 2,) arranged in pairs.

B represents the harrow-tooth seat, and the 40 same is formed in a single casting, and consists of a plate, preferably of a triangular shape in plan, provided with a transverse vertical groove or seat B', which in contour agrees with the character or form of tooth employed. 45 In this instance the tooth is what is commonly known as a "combined cultivator and harrow tooth."

C represents the tooth, which in cross-section is of an angular or diamond shape, and 50 is formed as a harrow-tooth at one end, as at

C', and as a cultivator-tooth, as at C², at its opposite end.

Other forms of harrow-teeth may be employed in connection with the herein-described holder, in which instances the contour 55 of the seat B' in cross-section would be changed to agree therewith. The holder is placed in position upon the side of the beam A, so that its elongated opening B² registers with one of the pair of transverse openings A' in said 60 beam. The other of said pair will then register with one of the series of notches B³. In this instance I have illustrated the central notch as being in registry with one of the 65 openings A', and the tooth C, being seated in said holder, will be maintained in a vertical position. By changing the holder so that other than the central notch will be in registry with the opening A' the inclination of the tooth will be changed either to a forward or 70 rearward inclination.

D represents a binding-staple, which is of a U shape and of a width agreeing with the distance from one of the notches to the opening B² of the holder. This staple embraces the shank 75 of the tooth and may have a slight indentation, as D², to receive the angle of the shank, or be perfectly round. One branch D' of the U-shaped staple is passed through the opening B² of the holder and the opening A', with 80 which it registers, and serves as a loose pivot, by which the holder is connected to the beam. The other of the branches D' of said staple is passed through the opposite opening A' in the beam, and is consequently embraced by 85 one of the notches B³, in accordance with the inclination it is desired to give the holder and tooth.

To the two branches of the staple are applied threaded binding-nuts D³, by which the 90 tooth is firmly bound in its seat.

To change the inclination of the tooth and seat, it is simply necessary to loosen the nuts D³, so that the staple may be slightly withdrawn, when, by reason of the elongated opening B² and the relative width of the staple, said holder may be moved laterally until the notches are out of line with and disengaged from the staple, and by a reverse movement 95 of the holder another notch is made to em- 100

brace the branch D' of the staple and the nuts tightened. To reverse the tooth, it is simply necessary to loosen the nuts sufficiently for the withdrawal of the tooth and its reintroduction.

I do not limit my invention to the elongated opening B³, as I may provide simply a circular opening, in which instance the staple would have to be wholly withdrawn to change its inclination.

Having thus described my invention, what I claim is—

1. The combination, with the beam A, having the openings A', of the holder B, having the angular seat B', the elongated opening B², arranged at one side thereof and registering with one of the openings A' and having the notches B³, arranged at the opposite side of the seat and in the edge of the holder, the tooth C, mounted in the seat, and the binding-staple D, passed through the openings A'

B² and notch B³ and provided with binding-nuts D³, substantially as specified.

2. The combination, with the beam A, having the openings A', of the holder B, having the angular seat B', the elongated opening B², arranged at one side thereof and registering with one of the openings A' and having the notches B³, arranged at the opposite side of the seat and in the edge of the holder, the angular tooth C, mounted in the seat, and the binding-staple D, passed through the openings A' B² and notch B³ and provided with the binding-nuts D³ and the intermediate notch D², for receiving the angular edge of the tooth, substantially as specified.

In testimony whereof I affix my signature in presence of two witnesses.

CLARENCE E. BEMENT.
